CLAIM

The ornamental design for a firearm with charging handle as shown and described.

DESCRIPTION

FIG. 1 is a left side perspective view of a firearm with charging handle in accordance with a first embodiment of my design;

FIG. 2 is a front elevational view of the firearm with charging handle of FIG. 1;

FIG. 3 is a rear elevational view of the firearm with charging handle of FIG. 1;

FIG. 4 is a left side elevational view of the firearm with charging handle of FIG. 1;

FIG. 5 is a right side elevational view of the firearm with charging handle of FIG. 1;

FIG. 6 is a top plan view of the firearm with charging handle of FIG. 1;

FIG. 7 is a bottom plan view of the firearm with charging handle of FIG. 1;

FIG. 8 is a left side perspective view of a firearm with charging handle in accordance with a second embodiment of my design;

FIG. 9 is a front elevational view of the firearm with charging handle of FIG. 8;

FIG. 10 is a rear elevational view of the firearm with charging handle of FIG. 8;

FIG. 11 is a left side elevational view of the firearm with charging handle of FIG. 8;

FIG. 12 is a right side elevational view of the firearm with charging handle of FIG. 8;

FIG. 13 is a top plan view of the firearm with charging handle of FIG. 8;

FIG. 14 is a bottom plan view of the firearm with charging handle of FIG. 8;

FIG. 15 is a left side perspective view of a firearm with charging handle in accordance with a third embodiment of my design;

FIG. 16 is a front elevational view of the firearm with charging handle of FIG. 15;

FIG. 17 is a rear elevational view of the firearm with charging handle of FIG. 15;

FIG. 18 is a left side elevational view of the firearm with charging handle of FIG. 15;

FIG. 19 is a right side elevational view of the firearm with charging handle of FIG. 15;

(Continued)

FIG. 20 is a top plan view of the firearm with charging handle of FIG. 15; and,

FIG. 21 is a bottom plan view of the firearm with charging handle of FIG. 15.

The broken lines having consistent dash lengths (dash-dash-dash) represent portions of the firearm with charging handle that form no part of the claimed design.

The broken lines having inconsistent dash lengths (long dash-short dash-long dash) in FIGS. 14 and 21 represent boundaries of the claimed design.
